HAND SPRAYING IMPLEMENT

Erich Klett, Stuttgart-Bad Cannstatt, Germany,
assignor to Robert Bosch Gesellschaft mit be-
schränkter Haftung, Stuttgart, Germany

Application January 20, 1938, Serial No. 185,960
In Germany January 25, 1937

7 Claims. (Cl. 299—97)

The present invention relates to hand spraying implements for spraying colour paint or like material of the type incorporating a pump which ejects the material to be sprayed through a nozzle and a driving motor built on to the pump.

In the known implements of this kind, the motor and the pump are either arranged one behind the other in the direction of spraying, or alternatively so arranged relative to each other that the shaft of the motor runs vertically to the stroke direction of the pump. In these forms of construction a special complete casing is necessary both for the motor and the pump, which is not always advantageous with regard to weight and ease in handling of the implement.

According to the present invention the pump and the motor are assembled with their longitudinal sides bearing against each other.

This advantageous use of space is accompanied by a considerable lessening of the weight and more handy construction of the implement.

One example of construction of the invention is shown diagrammatically in the accompanying drawing in which:

25 Figure 1 shows an axial section through the implement.

Figure 2 is an elevation of the implement seen against the direction of spraying.

The casing 1 encloses both the motor and the pump of the spraying implement and is provided on the lower side with a handle 2. At the end opposite the spraying nozzle, the casing 1 is sealed by an elliptical cover 3.

On the spraying nozzle side, there is provided 35 a cover 4 only for the motor part. In this cover 4 and an intermediate wall 5 inserted into the casing 1 is mounted the motor shaft 6, on which are secured the rotor 7 and a fan 29. The stator is shown by 8.

40 The end of the motor shaft projecting through the intermediate wall 5 is constructed as a pinion 9 which meshes with a gear wheel 10 mounted in the intermediate wall 5 and the cover 3. On this toothed wheel is provided at the same time 45 an inclined annular track 10a, in which a spherical groove 10b is made. The gear wheel is supported against axial pressures by a thrust bearing 11.

In the upper part of the casing 1 there is 50 provided a casing part 1a for the reception of the pump. In this casing a pump ram or piston 12 is guided so as to be axially displaceable and rotatable. It is pressed into the annular groove 10b of the toothed wheel 10 by a spring 32 through a collar 12a and a ball 13 lodged in its

hollow end. On the rotation of the gear wheel, the piston 12 performs a to-and-fro movement.

The piston 12 is provided with a control head 12b. The recesses on this control head 12b co-operate with the inlet opening 14a of a supply chamber 14 for a lubricating auxiliary liquid in such a manner that according to the extent of the turning of the piston 12 different amount of liquid is delivered per stroke. For setting the various turning positions the piston 12 can be turned from a hand rocking grip 27 (only in Fig. 1) via a rod not shown. The lubricating liquid supply chamber 14 is tightly closed by a closing screw 15.

From a reservoir 17, the material to be sprayed flows through an inlet opening 18 towards the pressure cylinder 30. An auxiliary piston is guided in this cylinder so as to be freely rotatable. It is guided back into its original position after each pressure stroke by a return spring 16.

The auxiliary piston 31 is moved to and fro by means of the auxiliary fluid in rhythm with the movements of the piston 12, and in so doing presses the material to be sprayed into the middle bore 20b of a nozzle needle 20 via a non-return valve 19. This nozzle needle is pressed with its front surface against the outlet of the pump with the aid of a cap nut 21, which is screwed into the front surface of the casing portion 1a, and by means of a flange 20a. The nozzle member 22 is longitudinally displaceable on the needle 20. By the spring 23, which is tensioned with the aid of a cover screw 24 it is pressed with its outlet opening against the tip of the needle, in conjunction with which it forms the nozzle valve. 35 In front of the nozzle outlet there is further fixed a front plate 26 with the aid of a cap nut 25.

From the handle of the implement there projects the operating lever 28 of an electric switch 40 lodged in the interior of the hand grip for switching the electromotor on and off in such a manner that it lies in the range of the fingers of the hand which operates the grip.

I declare that what I claim is:

1. In a portable hand operated liquid spraying device comprising a nozzle and a piston pump for ejecting liquid through said nozzle, said nozzle being in alignment with the axis of said pump, a driving motor drivably connected to said pump, 50 said motor being arranged with its axis parallel to the stroke axis of said pump and side by side therewith, and a handle arranged substantially transversely of the axes of said motor and pump.

2. In a portable hand operated liquid spraying 55

device comprising a nozzle and a piston pump for ejecting liquid through said nozzle, said nozzle being in alignment with the axis of said pump, a driving motor drivably connected to said pump, a casing for said pump, a casing for said motor, said casings being combined to form one common casing, said motor being arranged with its axis parallel to the stroke axis of said pump and side by side therewith, and a handle secured to said common casing and arranged substantially transversely of the axes of said motor and pump.

3. In a portable hand operated liquid spraying device comprising a nozzle and a piston pump for ejecting liquid through said nozzle, said nozzle being in alignment with the axis of said pump, a driving motor for said pump, said motor being arranged with its axis parallel to the stroke axis of said pump and side by side therewith, and a gear between said motor and said pump arranged at the end of the motor and of the pump opposite to said nozzle, and a handle arranged substantially transversely of the axes of said motor and pump.

25 4. In a portable hand operated liquid spraying device comprising a nozzle and a piston pump for ejecting liquid through said nozzle, said nozzle being in alignment with the axis of said pump, a driving motor for said pump, said motor being arranged with its axis parallel to the stroke axis of said pump and side by side therewith, a gear between said motor and said pump, a common casing for said pump, said motor and said gear, and a handle secured to said common casing and arranged substantially transversely of the axes of said motor and pump.

5. In a portable hand operated liquid spraying device comprising a nozzle and a piston pump for ejecting liquid through said nozzle, said nozzle being in alignment with the axis of said

pump, a driving motor for said pump, said motor being arranged with its axis parallel to the stroke axis of said pump and side by side therewith, a gear between said motor and said pump, a frontal cam disc driven by said gear, said pump including a pump piston, and a spring resiliently pressing said piston against said cam disc, and a handle arranged substantially transversely of the axes of said motor and pump.

6. In a portable hand operated liquid spraying device comprising a nozzle and a piston pump for ejecting liquid through said nozzle, said nozzle being in alignment with the axis of said pump, a driving motor for said pump, said motor being arranged with its axis parallel to the stroke axis of said pump and side by side therewith, a gear between said motor and said pump, a frontal cam disc driven by said gear, said pump including a piston, a spring resiliently pressing said piston against said cam disc, and a rolling member in one end of said piston and bearing against said cam, and a handle arranged substantially transversely of the axes of said motor and pump.

7. In a portable hand operated liquid spraying device comprising a nozzle and a piston pump for ejecting liquid through said nozzle, said nozzle being in alignment with the axis of said pump, a driving motor for said pump, said motor being arranged with its axis parallel to the stroke axis of said pump and side by side therewith, a gear between said motor and said pump, a frontal cam disc driven by said gear and having a groove therein, said pump including a piston, a spring pressing said piston against cam, and a rolling member in one end of said piston and bearing against said cam in said groove and a handle arranged substantially transversely of the axes of said motor and pump.
